UNITED STATES PATENT OFFICE.

CONSTANT AILLERY, OF NEW BEDFORD, MASSACHUSETTS, ASSIGNOR TO DRAPER COMPANY, OF HOPEDALE, MASSACHUSETTS, A CORPORATION OF MAINE.

LOOM-SHUTTLE.

No. 851,853.

Specification of Letters Patent.

Patented April 30, 1907.

Application filed April 27, 1906. Serial No. 313,955.

To all whom it may concern:

Be it known that I, CONSTANT AILLERY, a citizen of the United States, and a resident of New Bedford, in the county of Bristol and State of Massachusetts, have invented an Improvement in Loom-Shuttles, of which the following description, in connection with the accompanying drawings, is a specification, like letters on the drawings representing like parts.

This invention relates to loom shuttles, and it has for its particular object the production of novel and effective means for exerting the proper tension on the yarn or thread as it is drawn through the shuttle-eye.

In my present invention I have provided a friction device around which the thread passes in contact as it turns from the longitudinal passage in the shuttle to the side delivery-eye, the drag exerted upon the thread by engagement with the friction device keeping such thread under proper tension.

I have so arranged the friction device that it can be moved to bring a fresh engaging surface into acting position when the old surface becomes worn.

The various novel features of my invention will be fully described in the subjoined specification, wherein one practical embodiment of my invention is set forth, and particularly pointed out in the following claims.

Figure 1 is a top plan view of the delivery end of a loom-shuttle, with one embodiment of my invention applied thereto; Fig. 2 is a side elevation of the threading device or block detached, to more clearly illustrate the tension-producing means; Fig. 3 is a front view of the threading-block; and Fig. 4 is an enlarged cross-sectional detail on the line 4-4, Fig. 2.

I have herein shown my invention embodied in a loom-shuttle of the automatically self-threading type, the threading device or block being substantially that shown in United States Patent No. 769,914, granted September 13, 1904 to Northrop, but the particular threading device is not material to my invention, and the latter may also be used in other forms of loom shuttles.

Referring to Fig. 1 the shuttle-body 1 having an opening 2 to receive the filling-carrier or bobbin 3, and the side delivery eye 4, may be all of usual construction. The metallic threading block 5 has a longitudinal thread-

passage 6 having a slot-like thread entrance 7 at its rear end, and at the front end of the passage an inclined horn 8 is provided, Figs. 2 and 3, on the under side of the head 9 which overhangs the delivery-eye. A beak 10 crosses the front open end of the thread-passage and is overlapped by a shield 11 the filling-thread when drawn into the thread-passage 6 and under the beak, being directed downward automatically by the horn 8 and adjacent parts of the threading block into the delivery-eye.

In my present invention I have provided a friction device which engages the thread as it passes from the thread-passage and turns in a lateral direction to the delivery-eye. A steel pin 12 depends from the threading-block adjacent and back of the horn, and ordinarily such pin serves as a fixed guide for the thread. I provide this pin or guide with a covering of friction-producing material, such as felt, flannel, or other suitable material, the rough surface thereof acting upon the thread and exerting the requisite tension producing drag or strain thereon. A convenient mode of applying the material is to cement or otherwise secure a piece 13 of the material upon a cylindrical sleeve 14, slipped onto the pin and held thereon with a frictional fit so as to be immovable or held from rotation under normal conditions. It is unnecessary to head or upset the end of the pin as the bottom of the recess in the shuttle-body, cut to receive the threading block, will engage the lower end of the friction device and hold it in place. When one portion of the surface of the cylindrical friction producing covering 13 becomes so worn that it will not act properly upon the thread the block can be removed from the shuttle and the covering turned slightly by hand to present a fresh friction surface to engage the thread.

From the location of the friction device it will be seen that the filling-thread must draw across and partly around the same as it travels along from the front end of the thread-passage to the delivery-eye, and hence the tension is always exerted properly during the delivery of the thread.

The construction herein shown and described may be varied or modified in different details by those skilled in the art without departing from the spirit and scope of my invention as set forth in the appended claims.

Having described my invention what I claim as new and desire to secure by Letters Patent is:—

1. In a loom-shuttle having a delivery-eye and adapted to contain a supply of filling, means to direct the filling-thread to the eye, a thread-guide around which the thread passes to the delivery-eye, and a covering of friction producing material surrounding and normally immovable on said guide and acting upon the thread.
2. In a loom-shuttle having a side delivery-eye and a longitudinal thread-passage, a fixed thread-guide around which the filling-thread passes as it travels from said passage

to the delivery-eye, and a covering of friction producing material mounted on and normally held from movement relative to said guide to engage the thread, said covering being adapted to be turned on the guide to present a fresh engaging surface when desired. 20

In testimony whereof, I have signed my name to this specification, in the presence of two subscribing witnesses.

CONSTANT AILLERY.
